CLAIM

The ornamental design for an earphone, as shown and described.

DESCRIPTION

FIG. 1 is a perspective view of an earphone; FIG. 2 is a front elevational view of the earphone; FIG. 3 is a rear elevational view of the earphone; FIG. 4 is a top plan view of the earphone; FIG. 5 is a bottom plan view of the earphone; FIG. 6 is a right side elevational view of the earphone; and, FIG. 7 is a left side elevational view of the earphone. The broken lines in the drawings depict portions of the earphone that form no part of the claimed design.
